CRANKCASE VENTILATING SYSTEM

Wilfred W. Lowther, St. Paul, Minn., assignor to
 Donaldson Company, Inc., St. Paul, Minn., a
 corporation of Delaware

Application May 27, 1938, Serial No. 210,409

13 Claims. (Cl. 123—119)

This invention relates to internal combustion engines and more particularly to a novel system of obtaining a uni-directional flow of air, under pressure above that of atmosphere, outwardly from the intake manifolds of internal combustion engines, wherein the predominant pressure is above that of atmosphere. While the general principles involved in the system broadly referred to above are adapted for a wide variety of applications, they most readily adapt themselves for use in the ventilation of crank cases of internal combustion engines and, insofar as the present application is concerned, the description thereof will be limited to two such adaptions.

The "crank-case ventilating system" of my prior Patent No. 2,060,883 of November 17, 1936 has worked out in practice with a very high degree of success in connection with gasoline engines, but that system, being dependent for its operation upon a pressure differential in the engine air intake duct established by a restriction-producing device such as a carburetor or throttle valve, does not readily lend itself to use in connection with the Diesel type of engine, since in this latter type there is usually no carburetor or throttle valve in the engine intake to produce a pressure differential at different points therein. The present crank-case ventilating system makes use of the intermittent pressure surges produced in the engine's intake valve or valves to produce or aid in producing a forced circulation of air from the intake conduit through the engine's crank-case and, hence, is not restricted to use with engines having restriction-producing means such as throttle valves or carburetors in the intake.

As is well known, under operation condition of an internal combustion engine, the predominating pressure in the intake duct leading to the engine's combustion chamber is below atmospheric pressure, or in other words, is a partial vacuum. What is also a fact, although not so widely recognized, is that under the intermittent closing of the intake valve to any cylinder of an engine there is produced, for each valve closure, a pressure surge which is momentarily much greater than the predominating or mean average pressure in the intake conduit and which usually exceeds atmospheric pressure. The intermittent pressure surges produced by intermittent closing of the intake valve and resultant rapid stopping of the fast moving air column through the intake conduit may properly be referred to as the air-ram effects in the intake conduit and may hereinafter be referred to as such.

In accordance with the instant invention this intermittent air-ram effect in the intake conduit is harnessed to create or aid in creating a forced movement of air from the engine's air intake conduit to the crank-case. Preferably this is accom-

plished by extending a suitable conduit between the engine's intake conduit, at a point on the atmosphere side of the intake valve, and the crank-case and interposing in that connection or conduit a one-way check valve permitting free flow of air from the engine's intake conduit to the crank-case under intermittent air-ram effects or pressure surges but which prevents return flow of air from the crank-case under alternate lower pressure or partial vacuum conditions of the engine's intake. If air is to be circulated through the crank-case as a result of these pressure surges there must, of course, be provided an air outlet from the crank-case and although this may be direct to atmosphere, such crank-case outlet is preferably connected back to the engine's intake where it will be subject to a predominating vacuum condition of the engine's intake which will further aid in the circulation of air through the crank-case. Further, since it is desired to keep the crank-case as free as possible from dust and other foreign substance and since engines of the present day are almost universally equipped with air cleaners in their air intakes, the air supplied to the crank-case in the manner above described can easily be kept free from dirt by making the said connection or connections from the crank-case to the intake conduit at a point or points after the intake air cleaner.

In the accompanying drawings like characters indicate like parts throughout the several views.

Referring to the drawings:

Fig. 1 is a transverse sectional view through an internal combustion engine incorporating one embodiment of the invention;

Fig. 2 is an enlarged detail view in the side elevation with some parts broken away and some parts shown in section of the check valve of Fig. 1;

Fig. 3 is a transverse sectional view taken on the line 3—3 of Fig. 2 and looking upwardly, in respect to Fig. 2;

Fig. 4 is a detail sectional view illustrating a valve disc of different material than that illustrated in Figs. 1 and 2 but which may be substituted for the valve disc of Figs. 1, 2 and 3;

Fig. 1' is a transverse sectional view similar to Fig. 1 but illustrating another embodiment of the invention; and

Fig. 2' is an enlarged detail view of the check valve of Fig. 1' with some parts broken away and some parts shown in axial section.

The adaptation of the invention illustrated in Figs. 1 to 4 inclusive, will first be described. The engine illustrated in Fig. 1 is of the conventional character and, as previously stated, may be considered to be of the Diesel or oil burning type, since the intake conduit thereof incorporates no throttle valve or carburetor. Obviously, the engine illustrated may incorporate any number of

cylinders, but, for the purpose of this case, it may just as well be considered as a one-cylinder engine.

Of the conventional parts of the engine the cylinder block thereof is indicated as an entirety by 5, the cylinder bore thereof by 6, the piston by 1, the crank shaft by 8, the connecting rod by 9, the crank-case by 10, the cam shaft by 11, the intake valve operating cam by 12, the cylinder head by 13, the combustion chamber formed in the cylinder head above the cylinder bore 6, by 14, the spring-closed intake valve by 15, the roller tappet assembly by 16, the push rod by 17, and the intermediately pivoted rocker arm by 18.

In accordance with general practice the bottom of the crank-case 10 is closed by a removable oil pan 19, containing a suitable body of lubricating oil 20, and the valve actuating connections 17 and 18 are enclosed by a removable inspection plate 20 and a removable hood 21. Also in accordance with conventional practice, in overhead engines free communication is established between the valve mechanism chamber within the hood 21 and the crank-case 10. In accordance with the present illustration, such communication is established through passages 22, 23 and 24. The cylinder head 13 is provided with an intake port 25 that is controlled by the intake valve 15, and this intake port 25 is connected to atmosphere through a combustion chamber air intake duct 26 having applied therein a suitable air cleaner 27.

In accordance with the present illustration the ventilation inlet to the crank-case is made to one side thereof at 28 and the ventilation outlet from the crank-case is made from the valve mechanism chamber within the hood 21 at 29. The ventilation inlet 28 to the crank-case is connected to the combustion chamber air intake duct 26 at a point intermediate the air cleaner 27 and intake valve 15 by a relatively large area check-valve-equipped crank-case air intake duct 30, and the ventilation outlet in the crank-case is also connected to the combustion chamber air intake duct 26 at a point intermediate the air cleaner 27 and intake valve 15. This latter connection between the crank-case and intake duct, however, is preferably made through a relatively small area duct or conduit 31.

The check valve in the crank-case air inlet duct 30 is indicated as an entirety by 32, and in accordance with the present illustration, includes a two-part valve body 33, which parts are detachably secured together by screws or the like 34. The upper portion of the valve body is formed with an externally threaded tapered neck 35 that is screw threaded into combustion chamber intake duct 26, and the lower half of the valve body 33 is internally threaded at 36 to facilitate coupling to the conduit 30. The bore of the upper portion of the valve body 33 is coaxial with but of smaller diameter than that of the lower valve body so as to form, at the point of joinder of the upper and lower portions of the valve body, a shoulder 37 that affords a valve seat. In axially spaced relation to the shoulder 37 the lower portion of the valve body 33 is provided with a series of circumferentially spaced inwardly projecting supporting lugs 38, on which lugs 38 is seated a wire screen supporting disc 39. Loosely applied in the space between the valve seat shoulder 37 and the wire screen support 39 is an air pressure actuated valve disc 40, which valve disc, according to the illustration of Figs. 1 and 2, is made of thin sheet metal such,

for example, as very light sheet bronze. However, a valve disc made of relatively firm rubber composition has also been found suitable for the purpose, and such a rubber composition valve disc is illustrated in Fig. 4, wherein it is indicated by 40a. The valve disc 40 obviously must be of smaller diameter than that of the bore in the lower portion of the valve body 33, so that when it is seated upon the supporting screen 39, air will be permitted to pass therebetween and the walls of the bore 36 at points intermediate the supporting lugs 38; but it is equally important that the valve disc 40 be of greater diameter than that of the bore in the upper portion of the valve body 33, so that when it is in its elevated position against the valve surface 37, it will completely cut off and close the bore through the upper portion of the valve body.

Under operation of the engine the intake valve 15 will, of course, be opened during the downward intake strokes of the piston 1 so as to permit air to be drawn from the atmosphere through the intake conduit 21 and interposed air cleaner 27 to the combustion chamber 14 through the intake port 25, and said valve will be closed at the termination of the intake stroke of the piston and will remain closed during the succeeding compression, explosion and exhaust strokes of the piston. This rapidly occurring series of air intake cycles will produce a low pressure or relatively high vacuum condition in the intake conduit as a result of the restriction to air flow afforded by the conduit 26 and interposed air cleaner. In other words, under operating conditions of the engine the mean average pressure condition in the intake conduit, as measured, for example, by the conventional U tube manometer, will be a sub-atmospheric pressure or so-called partial vacuum. However, as previously indicated, the pressure in the intake conduit is not constant even under constant throttle and constant load but does, in fact, reach its lowest pressure or greatest condition of depression during the intake stroke of the piston, at which time the valve 15 is open; and then, upon closing of the intake valve 15, the abrupt stopping of the rapidly moving column of air through the intake conduit 26 results in momentary rise in pressure within the intake conduit, which often-times quite considerably exceeds atmospheric pressure. These pressure surges, while quite great in extent, are, nevertheless, of such short duration as compared to the duration of the extreme low pressure periods, that the average condition within the intake conduit is still considerably below atmospheric pressure.

OPERATION.—*Figs. 1 to 4 inclusive*

Under the above described conditions existing in the air intake conduit 26, under operation of the engine, the valve disc 40 will be elevated to its upper valve closed position, shown by dotted lines in Fig. 2, during all times that the pressure within the intake conduit 26 at the point of connection of the conduit 30 thereto is below that existing in the crank-case 10, during pressure-surge intervals caused by rapid closing of the valve 15 and resulting in pressure surges in the intake conduit 26 which exceed the pressure existing in the crank-case 10. Hence, each time the valve 15 is closed the pressure surge within the conduit 26 will momentarily be sufficient to open the valve 32 and cause injection of air from the intake conduit 26 through the valve 32 and conduit 30 to the crank-case, and this inter-

mittently injected clean fresh air will be returned to the intake conduit 28 through the crank-case outlet conduit 31.

By means of the conduit 31, which is open to flow of air in either direction, the crank-case is subject to the mean average pressure condition existing in the intake conduit 28, and this materially aids in the circulation of air through the crank-case. It has been found desirable to maintain a pressure condition in the crank-case slightly above that of atmosphere, so that the tendency will be to blow air out through any such small leaks as may occur in even a well sealed crank-case rather than draw air in through such possible leak; and this condition can quite readily be brought about with the system described by merely so proportioning the air-handling ability of the crank-case inlet 30 and crank-case outlet 31 as to obtain the desired pressure balance. In arriving at a proper balance to obtain this slight positive pressure condition in the crank-case, piston blow-by must, of course, be taken into consideration. Usually, the cross-sectional area of the conduit 31 will be much less than that of the conduit 30.

Figs 1' and 2'

In Fig. 1' the conventional parts of the engine illustrated are substantially like those indicated in Fig. 1 and are indicated by like characters plus the prime mark. In Fig. 1, however, the engine may, as previously indicated, be assumed to be of gasoline burning type since a carburetor 45, having a conventional butterfly throttle valve 46, is illustrated as being interposed in the intake conduit 28.

The ventilating system of Figs. 1' and 2' is similar to that of Figs. 1 to 4 inclusive, and includes a crank-case air inlet conduit 30' from the engine's intake to the crank-case having interposed therein a one way check valve 32' that is similar to that of Figs. 1 to 4, and a crank-case air outlet conduit 28' that connects the crank-case to the engine's intake conduit 28' in a manner similar to that of conduit 28 of Figs. 1 to 4. Insofar as the operation of this form of ventilating system is concerned, the check valve 32' could be exactly the same as the check valve 32 of Figs. 1 to 4 but a slight somewhat different form is illustrated for the purpose of example, and is, in fact, equally adapted to either of the forms herein illustrated. The valve 32' is provided with a pair of flap valve elements 48' that co-operate with opposite valve seats 37'. These valve flap elements are formed of resilient sheet material and are rigidly anchored each at one point by anchoring screws or the like 47. Under conditions of vacuum or sub-atmospheric pressure within the intake conduit 28', the flap valve elements 48' seat tightly against their respective seats 37' and prevent movements of air in a direction from the crank-case to the intake conduit, but under pressure surge conditions within the intake conduit when the pressure therein becomes above that within the crank case, the flap valve elements 48' readily yield and permit free passage of air from the intake conduit to the crank-case.

In this preferred adaptation of the invention to engines having throttle valve equipped carburetors in the intakes, the operation of a ventilating system is substantially the same as described in connection with Figs. 1 to 4, inclusive when the throttle valve is open and the engine operation under comparatively high speed or

load conditions, but when the throttle valve 46 is closed down to slow speed, low load or idling positions, ventilation of the crank case will be maintained largely by virtue of the extremely high vacuum or low sub-atmospheric pressure then present in the intake conduit at the point of connection of the conduit 29'. Otherwise stated, the velocity through the intake conduit 28' will decrease as the throttle valve 46 is moved from open toward closed position and will be so low when the valve 46 reaches its idling position shown in the drawings that the tendency for air to move into the crank case through the conduit 30' as a result of air ram effects in the conduit 28' will be very low. However, in about the same degree as the positive pressure air ram effects decrease under closing of the throttle valve, the degree of vacuum within the conduit 28' at the engine side of the throttle valve will be built up and will become increasingly more effective so that the velocity of air movement through the crank case will be maintained quite uniform under widely varying degrees of engine speed or load. When the throttle valve is fully closed to its low speed idling position illustrated, circulation will be maintained through the crank case largely by virtue of the average pressure differential within the intake conduit 28' at opposite sides of the throttle valve, as in the crank case ventilating system of my prior patent before herein identified, although even under these conditions there will be a lower pressure maintained within the crank case of the present system by virtue of the slight positive pressure pulsations or air ram effects within the conduit 28' at the point of connection of conduit 30'. Of course, when the throttle valve is open the restriction produced thereby will be so low that the system will function almost identically to that of Figs. 1 to 4.

What I claim is:

1. The combination with an internal combustion engine having a crank-case, a combustion chamber, an air intake duct leading to the combustion chamber, and an engine operated intake valve for intermittently opening and closing off communication between the air intake duct and combustion chamber, of a crank-case ventilating system comprising an air outlet from the crank-case, a conduit extending from the combustion-chamber air intake to the crank-case and having interposed therein a one-way check valve permitting air to flow only in the direction from the combustion-chamber air intake duct to the crank-case, whereby to utilize the instantaneous pressure surges produced in the intake under intermittent closing of the intake valve to force air from the engine intake duct into and through the crank-case.
2. The structure defined in claim 1 in which the said crank-case air outlet is connected to the combustion-chamber air intake, whereby it will be subject to the predominant low pressure condition of the intake.
3. The combination with an internal combustion engine of the reciprocating piston type, and having a crank-case, a combustion chamber, an air intake duct leading to the combustion chamber, and an engine operated intake valve for alternately opening and closing communication between the said air intake duct and combustion chamber, of a crank-case ventilating system comprising an air outlet leading from the crank-case, and a check-valve-equipped crank-case air intake conduit extending from the com-

bustion-chamber air intake duct, at a point on the atmosphere side of the intake valve, to the crank-case, said check valve permitting free flow of air from the engine air intake duct to the crank-case under pressure surges produced in the engine air intake duct under intermittent closing of the intake valve but preventing reverse flow of air from the crank-case under partial vacuum conditions existing in the intake conduit when the intake valve is open.

4. The combination with an internal combustion engine of the reciprocating piston type and which is provided with a crank-case, a combustion chamber, an air intake duct leading from atmosphere to the combustion chamber, and an engine operated intake valve for alternately opening and closing communication between the said air intake duct and the combustion chamber, of a crank-case ventilating system comprising at least two conduits between the said combustion-chamber air intake duct and the crank-case, one of said crank-case ventilating system ducts having incorporated therein a check valve permitting flow of air only in the direction of the crank-case.

5. The structure defined in claim 4 in which the check-valve-equipped conduit is proportioned to afford less restriction to the flow of air than is the other of said connections between the crank-case and combustion-chamber air intake conduit.

6. The structure defined in claim 4 in which the check-valve-equipped conduit is proportioned to afford less restriction to the flow of air than is the other of said connections between the crank-case and combustion-chamber air intake conduit.

7. The combination with an internal combustion engine having a crank-case, a combustion chamber, an air intake duct leading to the combustion chamber, and an engine operated intake valve for intermittently opening and closing communication between the air intake duct and combustion chamber, of a crank-case ventilating system comprising an air outlet from the crank-case, and a conduit connecting the combustion-chamber air intake duct to the crank-case and incorporating means for preventing flow of air through said ventilating system conduit in the direction of the combustion-chamber intake conduit but permitting free flow of air through said ventilating system conduit from said combustion-chamber intake conduit toward the crank-case when the pressure in the combustion-chamber intake conduit exceeds that in the crank-case.

8. The combination with an internal combustion engine having a crank-case, a combustion chamber, an air intake duct leading to the combustion chamber and having interposed therein a restriction producing means, and an engine operated intake valve for intermittently opening and closing communication between the air intake duct and combustion chamber, of a crank-case ventilating system comprising an air outlet duct leading from the crank-case to the intake duct at one side of the said restriction producing means, and a crank-case air intake duct extending from the combustion chamber air intake at a point on the other side of said restriction producing means to the crank-case and having interposed therein a one-way check valve permitting air to flow only in the direction of the crank-case.

9. The combination with an internal combustion engine of reciprocating piston type, said engine having a sealed crank-case, a combustion chamber, an air intake duct leading to the combustion chamber and having a throttle valve interposed therein, and an engine operated intake valve for alternately opening and closing off communication between said air intake duct and combustion chamber, of a crank-case ventilating system comprising an air outlet leading from the crank-case to the intake duct at a point on the engine side of said throttle valve, and a check valve-equipped crank-case air intake duct extending from the combustion-chamber air intake duct, at a point on the atmosphere side of the throttle valve, said check valve permitting free flow of air from the engine air intake duct to the crank-case under pressure surges produced in the engine air intake duct under intermittent closing of the intake valve but preventing reverse flow of air from the crank-case under partial vacuum conditions existing in the intake duct when the throttle valve is open.

10. The combination with an internal combustion engine having a sealed crank case, and an intake provided with a throttle valve therein, of a crank case ventilating system comprising conduits extending from the intake at opposite sides of the throttle valve and independently opening into the crank-case at points above the oil level in the crank-case, and a one-way opening check valve interposed in one of said crank-case ventilating system conduits for permitting free flow of air from the intake conduit to the crank-case, but preventing reverse flow of air therethrough.

11. The combination with an internal combustion engine having a sealed crank-case, and an intake provided with a carburetor therein, of a crank-case ventilating system comprising conduits extending from the intake at opposite sides of the carburetor and independently opening into the crank-case at points above the oil level in the crank-case, and a one-way opening check valve interposed in one of said crank-case ventilating system conduits that connects to the engine intake at the atmosphere side of the carburetor.

12. The combination with an internal combustion engine having a sealed crank-case, and an intake provided with a throttle valve-equipped carburetor, of a crank-case ventilating system comprising conduits extending from the intake at opposite sides of the carburetor throttle valve and independently opening into the crank-case at points above the oil level in the crank-case, and a one-way opening check valve interposed in the ventilating system conduit that connects to the engine intake at the atmosphere side of the carburetor throttle valve.

13. The combination with an internal combustion engine having a sealed crank-case, and an intake provided with a throttle valve-equipped carburetor, of a crank-case ventilating system comprising conduits extending from the intake at opposite sides of the throttle valve-equipped carburetor and independently opening into the crank-case at points above the oil level in the crank-case, and a one-way opening check-valve interposed in one of said ventilating system conduits.
